[57] CLAIM

The ornamental design for the wall unit bed, as shown and described.

DESCRIPTION

FIG. 1 is a front perspective view of a wall unit bed that incorporates my design, showing adjacent wall unit cabinets in phantom and showing the bed in an open position; FIG. 2 is the view of FIG. 1 with the bed in a closed position; FIG. 3 is a front elevational view thereof with the bed in the open position; FIG. 4 is a right side elevational view thereof, the left side elevational view being a mirror image thereof; FIG. 5 is a top plan view thereof; FIG. 6 is a front elevational view thereof, with the bed in the closed position; FIG. 7 is a right side elevational view thereof, the left side elevational view being a mirror image thereof; and, FIG. 8 is a top plan view thereof.
The broken lines are for environmental purposes only and form no part of the claimed design.
